UNITED STATES PATENT OFFICE.

WESLEY ROBERTS, OF MARTINSVILLE, ILLINOIS.

BABY-JUMPER.

SPECIFICATION forming part of Letters Patent No. 247,688, dated September 27, 1881.

Application filed July 16, 1881. (Model.)

To all whom it may concern:

Be it known that I, WESLEY ROBERTS, of Martinsville, in the county of Clark and State of Illinois, have invented a new and Improved 5 Baby-Jumper and Table Combined, of which the following is a full, clear, and exact description, reference being had to the accompanying drawings, in which—

Figure 1 is a plan view of my invention as 10 it appears when the parts are unfolded and the platform placed for use as a baby-jumper. Fig. 2 is a vertical sectional view of the same, taken at the line *x x* of Fig. 1. Fig. 3 is a cross-section of the same, taken on the line *y y* of Fig. 15 2; and Fig. 4 is a side elevation, partly in section, showing the parts folded for use as a table, the leaves being down.

Similar letters of reference indicate corresponding parts.

20 The frame or body of this device is composed of the upright end boards, A A', the side bottom pieces, B B, and the upper cross-bar, C. To the top of the upright A, and between the upward extensions *a a* thereof, is hinged the 25 lower end of the spring-pole G. This pole is preferably of hickory or similar strong and elastic wood, and is made in two parts, *g g'*, which are hinged at *g''*, and these parts are of a length about equal to the length of the cross-bar C, so that when the pole is folded the parts 30 *g g'* will fit between the uprights A A' and rest upon the said cross-piece, as shown in Fig. 4.

To the top of the upright A' is hinged the 35 folding support F, which is bifurcated, as shown in Fig. 3, and between the parts *ff* is placed the coiled spring H, upon which the spring-pole G rests when the parts of the device are unfolded for use as a swing or jumper. This support F is also of a length about equal 40 to the length of the cross-piece C, and is adapted to be folded down and rest upon the spring-pole G.

The side pieces, B B, of the frame are grooved or guttered out upon the inside, as shown at 45 *b b*, and in these grooves or channels the extension J is placed. This extension is provided at its outer end with the caster-wheel *j*, and is to be drawn out to the position shown in Fig. 2 to support the platform L along its center when it is used for the baby to jump upon, and this platform L is adapted to be placed

over and upon the whole device when it is folded up and to serve as a table, as shown in Fig. 4.

When the platform is placed upon the floor 55 for the baby to jump upon, the rear end of it is placed upon the extensions *ll* and under the cleat *l'*, all of which are secured to the outside of the upright A', and the leaves T T are supported upon the floor and made firm and steady by the legs or leaf-supports *kk*, hinged to the center part of the platform; and in order to render the frame and whole device secure and firm, I hinge to the sides of the upright A' the side wings or supports, K K, which 60 should be swung out, as shown in Fig. 3, when the device is used for jumping.

The under side of the platform, near the center, is provided with the projection *h*, which, when the platform is used as a table, fits between the parts *ff* of the folding support F, and serves to hold the platform in place. 70

The under side of the part *g'* of the spring-pole is recessed, as shown at *e*, for the reception of the upper end of the coiled spring H, 75 and this recess should be lined with tin or similar material, to prevent rapid wearing of the parts.

The child may be held in the swing by any suitable and safe means. The means I prefer to employ are shown clearly in Fig. 2, which consists, mainly, of cords or strips of cloth *dd*, of suitable length to be tied to the upper end of the pole and around the body of the child, so as to suspend the child in such a position 80 that it can just touch its toes to the platform, the cords or strips of cloth being kept away from the child's face and head by means of the ring *e*, which is tied to the cords or strips *dd* a short distance above the child's head, as 85 shown. By this device a child may amuse itself by jumping, whirling around, swinging, or sitting still, for hours together, thus relieving its mother of the care of the child, and the child being once placed in the swing, the mother 90 may always be sure of the safety of the child, and that it is not doing mischief, as the child cannot leave the platform of its own accord.

When the device is not used for amusing the child it is folded, as shown in Fig. 4, and thus 95 serves as a table.

Having thus fully described my invention,

I claim as new and desire to secure by Letters Patent—

1. The combined baby-jumper and table herein shown and described, consisting of a suitable frame, in combination with the hinged spring-pole G, hinged support F, and platform L, substantially as described.

2. The frame composed of the uprights A A' and grooved side pieces, B B, in combination with the extension J and platform L, substantially as and for the purposes set forth.

3. The folding support F, provided with the spring H, in combination with the hinged spring-pole G, substantially as and for the purposes set forth.

WESLEY ROBERTS.
